DESIGN FOR A TWIN TOP FLOWER VASE FOR HOLDING SHORT OR LONG STEM FLOWERS OR SIMILAR ARTICLE

Edwin Reynolds, Vineland, N. J.

Application May 15, 1944, Serial No. 113,596

Term of patent 14 years

(Cl. D29—28)

To all whom it may concern:

Be it known that I, Edwin Reynolds, a citizen of the United States, residing at Vineland, in the county of Cumberland and State of New Jersey, have invented a new, original, and ornamental Design for a Twin Top Flower Vase for Holding Short or Long Stem Flowers or Similar Article, of which the following is a specification, reference being had to the accompanying drawing, forming part thereof.

Fig. 1 is a side elevational view of a twin top flower vase for holding short or long stem flowers, showing my new design;

Fig. 2 is a sectional view of Figure 1, being divided in half; and

Fig. 3 is a top plan view of the article as shown in Fig. 1; and

Fig. 4 is a bottom plan view of the article as shown in Fig. 1.

I claim:

The ornamental design for a twin top flower vase for holding short or long stem flowers or similar article, substantially as shown.

EDWIN REYNOLDS.
